UNITED STATES PATENT OFFICE.

HUBERT C. HART, OF UNIONVILLE, CONNECTICUT.

TABLE-FORK.

SPECIFICATION forming part of Letters Patent No. 243,889, dated July 5, 1881.

Application filed January 26, 1881. (No model.)

To all whom it may concern:

Be it known that I, HUBERT C. HART, of Unionville, in the county of Hartford and State of Connecticut, have invented certain new and useful Improvements in Table-Forks, of which the following is a specification.

My invention relates to improvements in forks in which the tines, shank, and one-half of the handle are made of one piece of cold-rolled steel struck up in dies, and the other half of the handle of a separate piece made in like manner, the two halves of the handle being doweled and riveted, and the objects of my improvements are to produce a cheap, light, and durable fork. I attain these objects by making the fork of steel in the form illustrated in the accompanying drawings, in which—

Figure 1 is a plan view; Fig. 2, a longitudinal section on line $x-x$ of Fig. 1. Fig. 3 is a transverse section line on $y-y$ of Fig. 1, and Fig. 4 is a transverse section on line $z-z$ of Fig. 1.

I first blank out the tines $a-a$, shank b , and the half, c , of the handle A , all in one piece and from cold-rolled steel, and the other half, d , of the handle from a separate piece. I then strike these pieces, when cold, in dies which throw the metal into the form shown in the drawings—that is, with a central corrugation extending longitudinally through each of the tines and the shank, and a border-corrugation on the two halves of the handle. This border-corrugation forms a bead around the edge of each half upon the outside and a groove upon

the inside. After the parts have been thus struck up or swaged it is only necessary to place the two halves together, as shown, and secure them by rivets $m-m$, when the article is finished ready for use. The steel being cold-rolled requires no polishing, but may be tumbled, if desired, and also the handle may be japanned, or finished in any desired manner.

Although it is not necessary, I prefer to strike up cup-like depressions $o-o$ in the halves $c-d$ of the handle A , which, when said halves are placed together, will fit into each other and act as dowels to seat the halves properly upon each other, in which case I pass the rivets $m-m$ through the bottoms of said depressions, and with the rivet-heads sunk therein, as shown.

I claim as my invention—

1. The sheet-metal fork having central corrugations extending longitudinally through each of the tines and shank, substantially as described.

2. The handle A , formed of struck-up halves $c-d$, having the dowel-depressions $o-o$, and secured by rivets $m-m$, the heads of which rest in said depressions, substantially as described.

3. The herein-described fork, consisting of the two pieces of cold-rolled steel corrugated and riveted together, substantially as described, and for the purpose specified.

HUBERT C. HART.
